FUSE PLUG OF REGENERABLE TYPE

Roberto J. Peralta, Mexico City, Mexico

Application August 20, 1947, Serial No. 769,713
In Mexico February 26, 1947

7 Claims. (Cl. 200—125)

1

The present invention relates in general to electric fuse plugs, and in particular to some new and useful improvements in plugs of this kind which are of the "regenerable" type, being wholly different from those which so far have been known as will become apparent in the course of the following description. Before giving a specific description of the device as illustrated in the attached drawing, it is necessary to consider some conceptions concerning the essential conditions and regulations that this class of electric articles must meet.

One of the essential safety conditions required for the acceptance admission of a fuse plug of the "regenerable" type, is that said plug proves to be absolutely safe against blow out flames generated on the fusion of any part of the fuse element upon its failure to resist an overcharge of electric current. Another condition requisite to approval is, that there must exist an absolute contact between the fuse element and the electric contact terminals in order to avoid the formation of arcs. Another essential condition is that these articles be designed in such a way that, it be absolutely necessary to remove the plug from the socket or similar medium where it is placed in a circuit for replacement or regeneration of the fusible elements. Besides these conditions others are more or less imperative for a fuse plug of the type referred to in the present invention. For example, one other prerequisite is the absolute hermetic nature of the said plugs, for the purpose of avoiding also the escape of the gases formed upon melting of a fusible element thereof.

In plugs for similar use referred to in other patents of mine, there is employed a tablet, which like a star lodges a number of fusible elements each adapted to take an independent contact, and consequently to be placed in arbitrary order for the purpose of having a regenerable fuse offering a certain number of elements for substitution at a given moment when one of the said fuse elements is melted. Nevertheless I have found in the said plugs a series of difficulties, which, although they are not against the established regulations, still involve impediments and characteristics little desirable in products which it is intended to deliver to the consuming public with complete guarantees. Therefore, after much trial and experimentation I have succeeded in providing a fuse of the type described combining all the good conditions desirable and essential for this class of articles.

For the purpose of outlining the nature of the

2

invention the latter contemplates the provision of a hollow principal body of dielectric material, preferably of a thermosetting plastic, such as phenolic plastics or the like. The said body has an upper enlargement and a lower reduced portion arranged in such a way that on the reduced portion a threaded cap is superimposed and filleted on the outside and inside of the widened portion there is placed the tablet carrying the multiple fusible elements. A cap covers the said enlargement and a screw axially penetrates from the bottom of the reduced portion of the aforementioned body up to the central part of the cap into which it is screwed. When tightened, the screw causes a pressing adjustment of the said cap against the tablet by means of a flat contact spring, and at the same time the cap referred to is pressed tightly against the end of the widened portion of said body. Under these conditions, since a metallic feather or contact carried by the said filleted cap is pressed into contact with one of the lower ends of the fusible element carried in the said tablet, the aforementioned spring presses this end against said metallic feather or contact and provides a secure electrical joint under a very considerable pressure, and in this manner it meets the desired safety conditions referred to. Moreover, since the axial screw tightens the cover against the end of the enlarged portion thereby completely closing the open upper part of the body, and the said screw at the other end is provided with a conical finish and an enlarged head, it thus operates to provide an hermetic seal, and avoid all possibilities of the escape of smoke or flame.

One of the most detrimental results which have been observed in some other forms of regenerable fuses invented by me, is that, when an overcharge occurred and the element melted precisely in the portions calculated for a determined passage of amperes, the flame jet resulting occasioned the melting of the adjacent fusible parts, finally insulating some of the prongs or projections of the fusible star. The corresponding undesired destruction which resulted in inoperability of said adjacent elements, which of course, was an undesirable result for the public.

Objects and features of the invention are to provide regenerable type fuse plugs of the character described that will meet safety regulations, that will be effective for the intended purposes, and that will be simple to assemble and use. Other features and objects will appear herein-after.

55 The characteristic details of the present inven-

tion will be seen more easily in the course of the description hereinafter set forth, wherein it will be possible to observe with greater clearness the objectives, advantages and differences of my invention, as compared to others known. The drawings and description referred to illustrate a preferred form of execution, and similar reference characters denote the same parts throughout the various figures shown.

In the drawings:

Fig. 1 shows in conventional exploded perspective a fuse plug of the regenerable type in which the invention is embodied;

Fig. 2 illustrates a longitudinal section of the plug referred to, taken on its principal axis;

Fig. 3 is an end view of the tablet carrying the fusible element viewed from the right of Fig. 1;

Fig. 4 is an end view of the tablet, viewed from the left of Fig. 1; and

Fig. 5 is a perspective view of one form of fusible element.

Before proceeding to describe the invention in detail, with reference to the figures shown, I wish it to be understood that only a preferred form of execution for the practical use of the invention has been illustrated but that I do not not intend thereby to limit myself to only this preferred form of execution, and practical realization of the invention.

Making specific reference to the drawings in this invention, the fuse comprises a principal hollow body 10 of dielectric material, such as phenol thermosetting plastic providing a cylindrical portion 11 opened at 12, and a reduced cylindrical portion 13 joined to the first portion 10 by a truncated conical portion 14. The reduced portion 13 at its outer end has a central opening 15, with inturned edges 16 forming a small mouth. The bottom 17 of the said portion 13 is formed as a ring-like base offering the diametrically opposed projections 18 and 19. In the truncated conical portion 14, a window at 20, permits the passage to the inside of a contact part 21, of a small connecting strip 22, to which there is soldered at 23 a threaded metallic cap 24. This cap 24 is filleted over at 25 to lie on the ring-like base at the bottom 17 of the portion 13 and also projecting into the spaces between the diametrically opposed protuberances 18 and 19. The protuberances 18 and 19 thereby prevent the metal cap 24 from rotating on the cylindrical portion 13. Thus a minimum exercise of force or strain at the soldering joint 23 of the connecting strip 22 is provided.

A fuse element carrying member or tablet 26 is provided. This tablet 26 has a principal cylindrical portion 21. Recesses 28 are provided in one face. A centralized groove 29 is provided on the opposite face. A bevel 30 on the latter face provides a ledge 31. A central hole 32 is provided in the body 26 and distributed on a circumferential line having as center the axis of hole 32, said tablet 26 has a plurality of radially arranged holes 33 into each of which there are introduced one of the multiple prongs 34 of a star-like fusible member 35.

The star-like fusible member 35 in the embodiment shown has six prongs or fusible elements 34. The member 35 as seen in Fig. 5 has a disc-like portion 35a within whose periphery the prongs 34 are integral. The latter are bent downwardly to extend in parallelism with the axis of the disc portion 35a. Each has a weakened or thinned portion 34a designed to fuse with a current overload. The disc 35a is cut out to provide

a hole 36 with upstanding substantially pointed lugs 37 corresponding in number with the prongs 34. An insulating washer 38 is mounted around the upstanding lugs 37 and these are then bent 5 around to overlie the latter and to secure it to the face of disc-like portion 35a as seen in Fig. 1. These bent over tips then serve as an electrical contact as will presently be described. In mounting member 35 to the tablet 26 between the disc-like portion 35a and a low relief surface 39 of tablet 27, there is inserted an asbestos washer 40, which cooperates with the washer 38 to protect the disc-like portion 35a of the fusible element 35 against the action of the jets of flame 15 produced on fusion of the weakened portions 34a of prongs 34 in the event of a current overcharge. Washer 40 as well as 39 have bores at their centers aligned axially with tablet hole 32 for the passage of an assembling screw 41, as will be explained later on. The fusible prongs 34, after their insertion through the tablet holes 33, are bent in their free ends as shown at 42 to lie against and on the ledge 31 of tablet 26, and further bent to lie on the face or bevel 30, as 25 shown at 43.

As the small contact strip 22 introduced at 20 presents the feather or spring contact part 21 bent against the inclined inner face of the portion 14 it lies substantially in the same angular plane 30 as that of bevel 30. Consequently their planes are parallel. Therefore a portion 43 of one of the fusible elements 34 will rest on and against the aforementioned feather or part 21. Then sufficient pressure on tablet 26 will be enough 35 to maintain a firm contact, between the part 21 and a part 43 in accordance with regulations.

For covering the open end 12 of the widened portion 11 of body 10 there is provided a cover or cap 44, provided with a skirt 45 for covering 40 the external and upper peripheral surfaces of portion 11, while a washer 46 positioned within the cover 44 functions as a seal when the cover 44 is tightened against the upper edges of said widened portion 11. The portion 11 of body 10 has on its external surface a groove or channel 46 which extends in the direction of its major axis, and the cover 44 in its skirt 45 is provided internally with protuberance or small rib 47 adapted to fit slidably into the groove 46 when 50 the cover 44 is applied to body 10 so that the cover will be held against any possible rotary movements. The internal wall of the cylindrical portion 11 of the body 10 has one or more longitudinally extending ribs 46b which are engageable in longitudinal grooves 27b provided in the wall portion 27 of the tablet 26. These grooves 27b serve with the ribs 46b to prevent rotation 55 of the tablet 26 and, also, to position the ends 43 of the fusible prongs with respect to the contact part 21 of member 26.

The cover 44 at its center lodges firmly the nut 48, on the inner side of which there is secured a folded leaf spring 49, the feet of which have holes 50, 50a, it being observed that the hole 60 50a on the loose foot 49a be sufficiently wide for permitting the free passage without contact of the upper end of screw 41 suitable for threading into nut 48.

The screw 41 in turn carries a head 51 of 70 dielectric material like that of body 10. This head is fluted peripherally at 52 and has a rim 53 suitable for pressing said head 51 against the portion 25 of the metallic cap 24. The head is shaped to such a form that it provides an insertion frame for the screw 41 axially and has a

tapered or frustro-conical portion 54. The rim 53 pressing against the portion 25 functions as an hermetic seal and the conical body 54 to which the screw is secured as by a small deformed portion 41a in the screw and a head 55 closes the opening 15 in the bottom portion 13 of the body 10. To avoid the need for a screw driver, the portion 41b of the screw just below the head 55 is substantially square in section and fits into a square recess 51b in the conical body 54 so that when the screw is secured in place by the deformed or riveted portion 41a, the screw will rotate upon rotation of head 51. No screw driver will be required. The head 55 of screw 41 functions as a contact part to contact with one current terminal of a socket (not shown), while the metallic threaded cap 24 makes contact with the other socket terminal. In these conditions, and after the parts have been positioned for assembly in the manner shown in Fig. 1, the screw 41 is screwed into nut 48, and the flat spring part 49 makes contact with the nut 48 and the screw 41, while the other loose leg 49a makes contact by pressure with the star-like portion 37 of the fusible element 35 and through one of the prongs 34, by means of its bends 42 and 43 closes the electric circuit making contact with the part 21 of member 22 and the metallic cap 24, placing the fusible element 35 in series with the terminals in the socket (not shown). When an overload of current causes the particular prong 34 to fuse, the flame or gases developed are prevented from escaping by the hermetic seals provided between the separable parts of the device. To reset the device for use, it is necessary to remove the entire plug 10 from the socket and thereafter to unscrew the screw 41 from nut 48 and remove the cover 45 from the cylindrical portion 11. The tablet 26 is then removed and rotated to bring a fresh one of the prongs 34 of element 35 into position for engagement with the contact part 21. The parts are then reassembled and the plug screwed back into the socket. Since the entire plug must be removed from the socket, for such purposes, dangers of electric shock are eliminated.

While a practical and preferred form of putting the invention into practice has been described, I wish to make it clear that it is not my purpose to limit my rights exclusively to the constructions and specific disclosures shown and described, because in the industrial application changes and modifications within the spirit and scope of the claims defining the invention are possible and are contemplated. Therefore, the limitations in practice should only be bounded by the scope of the claims appended hereto.

What is claimed is:

1. Improvements in fuse plugs of the regenerable type comprising a principal hollow body, a metallic threaded cap mounted on said body, a contact member electrically connected to said cap and extending into said body, said body having an open end, a multiple fuse bearing tablet member removably carried in said body, a multiple fuse mounted on said tablet member, said fuse having a plurality of prong-like parts and a central part, a cover removably mountable on said body over said open end, a contact spring carried by said cover and engageable with said central part of said fuse, a screw member for securing said cover member to said body, said screw member serving to draw said cover onto said body and thereby to press said spring against said central part of said fuse and, also, to press

one of said prong-like parts against said contact member to complete an electrical series circuit, and means to prevent rotation both of said tablet member and said cover when said screw is loosened and tightened.

2. Improvements in fuse plugs of the regenerable type comprising a principal hollow body, a removable tablet-like member, a multi-pronged fusible element carried by said tablet-like member, a removable cover for said body, an axially extending screw for securing said cover to said body, a contact member secured to said cover for engaging said fusible element, a metallic threaded member positioned on said body, protuberances upon said body to prevent rotation of said threaded member, a contact strip electrically secured to said threaded metallic member and extending into said body for contact with one of the prongs at a time of said fusible element, and said screw being in electrical contact with said contact member.

3. Improvements in fuse plugs of the regenerable type comprising a principal hollow body, a removable tablet carried within said body, a multi-pronged fusible element mounted on said tablet, contacts for electrically connecting one of the prongs of the fusible elements at a time in an electrical circuit, a removable cover for said body and an axially extending screw for securing said cover to said body, a threaded metallic cap mounted externally of said body, and said body having an annular opening in one end defined by a ledge, protuberances on said ledge, and said cap having portions fitted on said ledge about said protuberances to prevent rotation of said metallic cap relative to said body, one of said contacts being electrically connected to said metallic cap and extending into said hollow body for contact with one of said prongs at a time and a second of said contacts being mounted on said cover for engagement with said fusible element, said second of said contacts being electrically connected with said screw.

4. Improvements in fuse plugs of the regenerable type comprising a principal hollow body, a threaded metallic cap mounted on said body, a removable tablet carried by said body, a multi-pronged fusible element mounted on said tablet, contacts for electrically connecting one of the prongs of said fusible elements at a time in an electrical circuit including said cap, a removable cover for said body, an axially extending screw for securing said cover to said body, a striated head of dielectric material for said screw, and a conical sleeve portion of dielectric material for said screw for providing a sealing joint with an opening defined by portions of said body for sealing the opening, said head also having a sealing portion engageable with a surface of said metallic cap adjacent said opening.

5. Improvements in fuse plugs of the regenerable type comprising a principal hollow body, a conductive cap mounted on said body, a removable tablet carried by said body, a multi-pronged fusible element mounted on said tablet, contact means for electrically connecting one of said prongs at a time in an electrical circuit including said cap, a removable cover for said body, a screw for securing said cover to said body, said tablet being substantially cylindrical and having a recess in one end face and radially distributed holes into each of which one of the prongs extends, and having a peripheral edge and a beveled edge around which portions of said prongs are bent, said fusible element

7 having a portion fitted within said recess, a heat resisting washer underlying said element within said recess, and an insulating washer overlying said element and aligned with said first-named washer to protect said element from flame developed upon fusion of any of said prongs.

6. Improvements in regenerable fuse plugs as per claim 4, in which said conical sleeve portion of dielectric material is secured to said screw as by a deformed portion.

7. Improvements in fuse plugs of the regenerable type comprising a principal hollow body of dielectric material, a metallic threaded cap positioned on said body externally thereof, a contact member electrically connected to said cap and extending into said body, said body having an open end, a multiple fuse bearing tablet member removably carried in said body, a multiple fuse mounted on said tablet member, said fuse having a plurality of prong-like parts and a central part, a cover of dielectric material removably mountable on said body over said open end, a contact spring secured to said cover and engageable with said central part of said fuse, a metallic screw member for securing said cover member to said body, said screw member being electrically connected to said contact spring, said screw member serving when tightened to draw said cover onto said body and to

5 press said contact spring against said central part of said fuse and, also, to press one of said prong-like parts against said contact member to complete an electrical series circuit, rotation preventing means within said body engageable with said tablet member, and additional inter-engaging rotation-preventing means on said body and on said cover whereby rotation is prevented both of said tablet member and of said cover 10 both when said screw is loosened and tightened, said body, also, having external protuberances in a portion thereof and said metallic cap having portions fitting about said protuberances to prevent rotation of said metallic cap relative to said body.
